UNITED STATES PATENT OFFICE.

MALONE WHELESS AND JAMES D. DARDEN, OF WASHINGTON, DISTRICT OF COLUMBIA; SAID WHELESS ASSIGNOR TO SAID DARDEN.

TELEPHONE-TRANSMITTER.

SPECIFICATION forming part of Letters Patent No. 352,900, dated November 16, 1886.

Application filed March 5, 1886. Serial No. 194,159. (No model.)

To all whom it may concern:
Be it known that we, MALONE WHELESS and JAMES D. DARDEN, citizens of the United States, residing at Washington, in the District 5 of Columbia, have invented certain new and useful Improvements in Telephone-Transmitters; and we do hereby declare the following to be a full, clear, and exact description of the invention, such as will enable others skilled in 10 the art to which it appertains to make and use the same.

Our invention relates to telephone-transmitters, and has for its object to provide a transmitter which will admit of more powerful currents being sent through and overcome the 15 "grinding" at the receiver, so common in telephones now in use. This grinding of the carbon is caused by the crystalline formation of the carbon, and acts as a great impediment to 20 the articulation of the telephone.

By our improvements the surface of the carbon is kept perfectly smooth, maintaining a softness which totally destroys the metallic ring characteristic in telephony, and gives the 25 advantage of using greater power from the battery without decreasing the utility of the carbon as a "resistant," and admits of transmitting messages over long distances without the loss of articulation. The carbon is kept 30 continually in a moist state by means herein-after more fully described. These objects we attain by the device illustrated in the accompanying drawings, in which—

Figure 1 represents a vertical sectional view 35 of our transmitter; and Fig. 2 a similar view of the transmitter with an induction-coil, "cut-out" mechanism, and receiver.

Similar letters refer to similar parts throughout the several views.

40 The letter I indicates a sounding-box provided with the usual mouth-piece, i, a diaphragm, D, being secured at its top and bottom by means of screws. Attached to the diaphragm is a metallic cup, A, having an opening, a, in the under side thereof to receive one end of a tube, C, filled with a spongy substance, D', the other end of said tube being received in a vessel, C', which is placed in a convenient position, and secured by a strap, c, or 45 50 other means. In the rear portion of the me-

tallic cup A is placed a small quantity of powdered carbon "filtering-paper" or other absorbent, and in front of which is placed a small carbon button or electrode B. The vessel C being filled with water or other liquid, the carbon button is kept in a moist condition by capillary attraction. The liquid being carried up the tube through the medium of the spongy substance saturates the powdered carbon or other absorbent, and the carbon button B, being pressed against the absorbent, partakes of the moisture, and becomes soft and yielding, thus presenting to the opposite electrode a soft and smooth contact-surface.

The electrode J is carried by a spring, E, 65 which, together with an adjusting device consisting of a bracket, thumb-screw, and jam-nut, is secured to the box by means of a screw. In the transmitter shown in Fig. 1 it will be seen that the direct battery-current is represented as operating without the induction-coil, the current passing from the battery to the diaphragm, thence to the metallic cup, through the contact-button B to the contact J, thence to the line-wire H at a by means of the spring 70 E. A "cut-off," Fig. 2, consisting of a spring, n, and two metallic contacts, m and m', serves to open the local battery-circuit while the speaker is listening, and gives the induction-current coming into his receiver less resistance than it otherwise would have if it passed around the coil through which the battery-circuit is flowing, as is the case with the transmitters in general use.

One pole of the battery R leads to the point 85 P, thence down to the spring n to the contact-point, passing through the opposite metallic contact m' to the diaphragm D, thence to the metallic cup and carbon to the opposite electrode J; up the spring E to a, thence to the 90 induction-coil S, and back to the other pole of the battery.

When the transmitter is not in use, the point of contact is always open; but when it is used it is closed by a pressure of the finger upon 95 the button of the contact m, which makes the induction-coil effective.

We are aware that an electrode of bibulous paper moistened with water fed by capillary attraction, and placed between metallic plates, 100

has heretofore been used. Such a construction differs materially from that which is herein sought to be claimed, in that our invention consists, essentially, of an absorbent body and a body of hard carbon, the two constituting one of the electrode-contacts.

Having thus fully described our invention, what we claim, and desire to secure by Letters Patent, is—

1. A telephone-transmitter, one of whose electrodes consists of a body of moistened absorbent conducting material adjacent to the diaphragm, and a button of hard carbon constituting the electrode-contact, substantially as specified.

2. A telephone-transmitter, one of whose electrodes consists of a body of moistened powdered carbon adjacent to the diaphragm, and a button of hard carbon constituting the electrode-contact, substantially as specified.

3. A telephone-transmitter having a diaphragm provided with a central socket containing a body of moistened powdered carbon, and a button of hard carbon in front of said

powdered carbon, the two forms of carbon constituting one of the electrodes, substantially as specified.

4. A telephone provided with an absorbent electrode composed of powdered carbon, and a button of hard carbon, a feed-reservoir for furnishing fluid thereto, and a capillary conveyor intermediate between the electrodes and reservoir, substantially as described.

5. A telephone-transmitter having a diaphragm provided with a central socket containing a hard carbon button, a body of powdered carbon intermediate between said button and diaphragm, a feed-reservoir, and a capillary conveyer between the reservoir and powdered carbon, substantially as described and shown.

In testimony whereof we affix our signatures in presence of two witnesses.

MALONE WHELESS.
JAMES D. DARREN.
